UNITED STATES PATENT OFFICE.

JAMES M. HALFPENNY, OF JUNIATA, PENNSYLVANIA.

SAFETY-TIE.

1,146,248.

Specification of Letters Patent. Patented July 13, 1915.

Application filed July 14, 1914. Serial No. 850,975.

To all whom it may concern:

Be it known that I, JAMES M. HALFPENNY, a citizen of the United States, residing at Juniata, in the county of Blair and State of Pennsylvania, have invented a new and useful Safety-Tie, of which the following is a specification.

The device forming the subject matter of this application is a railroad tie.

10 One object of the present invention is to provide a novel form of fastening means for holding the rail in place, the fastening means embodying a tie plate of novel form, and novel means being provided for preventing relative movement between the rail, the tie plate and the tie.

Another object of the invention is to improve the construction of the tie and to render the same of unusual strength.

20 Another object of the present invention is to provide in a tie of the form of an I-beam, closures for the ends of the I-beam, whereby the same will be prevented from moving endwise in the ballast.

25 It is within the scope of the invention to improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

In the accompanying drawing:—Figure 40 1 shows the invention in top plan; Fig. 2 is a side elevation, the rails being shown in section; Fig. 3 is a fragmental transverse section taken approximately on the line 3—3 of Fig. 2, parts being omitted; Fig. 4 is a 45 fragmental top plan of the tie; Fig. 5 is a side elevation showing a modified form of the invention; Fig. 6 is a side elevation of the connecting bolt; Fig. 7 is a side elevation showing a modified form of the invention; Fig. 8 is a cross section showing a 50 modified form of the invention.

In carrying out the present invention there is provided a tie denoted generally by the numeral 1. The tie 1 may be of any desired form, but in the present instance is shown as consisting of an I-beam, compris-

ing an upper flange 2, a lower flange 3 and a web 4 connecting the flanges as is thoroughly understood in the art.

In order to prevent the tie 1 from moving 60 endwise in the ballast, closures 5 are applied to the ends of the tie and extend between the flanges 2 and 3. The closures 5 are equipped with spaced tongues 6, lying upon opposite sides of the end portions of 65 the web 4 and mounted in the tongues 6 and in the web 4 are securing devices such as bolts 7.

In carrying out the present invention, recesses 8 are formed in the upper flange 2. 70 The upper flange 2 is upwardly arched as indicated at 9, between the ends of the recesses 8, the ends of the recesses 8 defining shoulders 10. The lower flange 3 of the tie is upwardly arched as indicated at 11. 75 Resting in each recess 8 is a tie plate 12. The upwardly arched portions 9 and 11 of the tie are co-extensive in length with the tie plate 12. The tie plate 12 preferably is fashioned from wood or from some other 80 material having the characteristics of that substance. The lower face of the tie plate 12 is concaved to form a recess 14 receiving the upwardly arched portion 9 of the tie, the ends of the tie plate 12 abutting against 85 the shoulders 10. Formed in the upper surface of the tie plate 12 is an intermediate transverse notch 15 receiving a rail 16.

In the upper face of the tie plate 12 are formed terminal transverse notches 17. 90 Fasteners 18 are supported by the tie plate 12 and engage the rail 16. the fasteners 18 terminating in fingers 19 registering in the terminal notches 17 of the tie plate 12. As clearly shown in Fig. 4, polygonal holes 20 95 are formed in the upper flange 2 within the contour of the recess 8. Securing devices such as bolts 21 pass through the openings 20, the bolts 21 being provided with polygonal portions 22 adapted to register against 100 rotation in the holes 20. The bolts 21 pass upwardly through the tie plate 12 and through the fasteners 18, nuts 23 being applied to the upper ends of the bolts, the nuts 23 bearing upon and engaging the fasteners 18.

The distinguishing characteristic of the modification shown in Fig. 5 consists in the fact that the bottom of the recess in the upper flange of the tie is flat, as shown at 24. 110

In the modification depicted in Fig. 7, the tie plate and the tie are equipped with mutu-

ally interengaged transverse corrugations 25. However, as shown in Fig. 8, the corrugations indicated at 26, may lie longitudinally of the tie, if preferred.

5. Owing to the fact that the tie is upwardly arched as indicated at 9 and at 11, and owing to the fact that the side plate 12 is of arched construction, the strength of the structure is enhanced.

10. Even though the bolts 21 should become displaced accidentally, the tie plates 12 cannot move in the direction of the length of the tie 1, owing to the fact that the tie plates are terminally engaged by the shoulders 10.

15. The rails 16, therefore cannot be spread apart.

Although the tie is shown as provided with but two recesses 8 and attendant parts, it will be understood readily that the number of recesses may be increased in number, to any desired extent, should it be necessary to employ the structure as a switch tie, supporting more than two rails.

The corrugations shown at 25 and 26 may be dispensed with, as will be obvious from the showing of Figs. 2 and 5. The smooth bottomed insulating plate shown in Figs. 2 and 5 is preferable when the plate is fashioned from pine, oak or some other suitable wood.

Having thus described the invention, what is claimed is:—

1. In a device of the class described, a tie; and a tie plate resting on the tie, the upper edge of the tie being upwardly arched below the tie plate, and the plate having a concavity receiving the upwardly arched portion of the tie.

2. In a device of the class described, a tie; and a tie plate resting on the tie, the upper edge of the tie including an upwardly arched portion, and the plate having a concavity in which the upwardly arched portion of the tie is received, the tie being provided in its upper edge with transverse, plate-engaging shoulders.

3. In a device of the class described, a tie; a tie plate resting on the tie, the upper edge of the tie including an upwardly arched portion co-extensive in length with the plate, and the plate having a concavity in which the upwardly arched portion of the tie is received.

4. In a device of the class described, a tie; and a tie plate resting on the tie, the upper edge of the tie including an upwardly arched portion co-extensive in length with the plate, and the plate having a concavity in which the upwardly arched portion of the tie is received, the tie being provided in its upper edge with transverse, plate engaging shoulders.

5. In a device of the class described, a tie; and a tie plate resting on the tie, the upper and lower edges of the tie including up-

wardly arched portions co-extensive in length with the plate, and the plate having a concavity receiving the upwardly arched portion of the upper edge of the tie.

6. In a device of the class described, a tie; and a tie plate resting on the tie, the upper and lower edges of the tie including upwardly arched portions co-extensive in length with the plate, the plate having a concavity receiving the upwardly arched portion of the upper edge of the tie, the tie being provided in its upper edge with transverse, plate engaging shoulders.

7. In a device of the class described, a tie in the form of an I-beam and including upper and lower flanges; and a tie plate resting on the upper flange, the upper flange including an upwardly arched portion co-extensive in length with the tie plate, and the tie plate having a concavity in which the upwardly arched portion is received.

8. In a device of the class described, a tie in the form of an I-beam and including upper and lower flanges; and a tie plate resting on the upper flange, both flanges including upwardly arched portions co-extensive in length with the plate, the plate having a concavity in which the upwardly arched portion of the upper flange of the tie is received.

9. In a device of the class described, a tie in the form of an I-beam and including upper and lower flanges; and a tie plate resting on the upper flange, both flanges including upwardly arched portions co-extensive in length with the plate, the plate being provided with a concavity in which the upwardly arched portion of the upper flange of the tie is received, the upper flange of the tie being provided with shoulders engaging the ends of the plate.

10. In a device of the class described, a tie in the form of an I-beam and including upper and lower flanges, the upper flange being provided with a recess and being upwardly arched between the ends of the recess; a tie plate resting in the recess and having a concavity receiving the upwardly arched portion of the upper flange of the tie, the lower flange of the tie including an upwardly arched portion co-extensive in length with the recess.

11. In a device of the class described, a tie in the form of an I-beam and including a web and upper and lower flanges; and a closure for the end of the tie, the closure extending between the flanges; and means for connecting the closure with the web.

12. In a device of the class described, a tie in the form of an I-beam and including a web and upper and lower flanges; a closure for the end of the tie and extended between the upper and lower flanges of the tie, the closure including a tongue overlapped upon

the web of the tie; and a securing device connecting the tongue of the closure with the tie.

13. In a device of the class described, a tie; and a tie plate resting on the tie, the upper and lower edges of the tie including upwardly arched portions, and the plate having a concavity receiving the upwardly arched portion of the upper edge of the tie.

14. In a device of the class described, a tie; and a tie plate resting on the tie, the upper and lower edges of the tie including upwardly arched portions, the plate having a concavity receiving the upwardly arched portion of the upper edge of the tie, the tie being provided in its upper edge with transverse, plate-engaging shoulders.

15. In a device of the class described, a tie in the form of an I beam and including upper and lower flanges; and a tie plate resting on the upper flange, the upper flange including an upwardly arched portion, and the tie having a concavity in which the upwardly arched portion is received.

25 16. In a device of the class described, a

tie in the form of an I beam and including upper and lower flanges; and a tie plate resting on the upper flange, both flanges including upwardly arched portions, the plate having a concavity in which the upwardly arched portion of the upper flange of the tie is received.

17. In a device of the class described, a tie in the form of an I beam and including upper and lower flanges; and a tie plate resting on the upper flange, both flanges including upwardly arched portions, the plate being provided with a cavity in which the upwardly arched portion of the upper flange of the tie is received, the upper flange of the tie being provided with shoulders engaging the ends of the plate.

In testimony that I claim the foregoing as my own, I have hereto affixed my signature in the presence of two witnesses.

JAMES M. HALFPENNY.
